UNITED STATES PATENT OFFICE.

WILLIAM J. RAPPLEY, OF BILLINGS, MONTANA.

DRIVE-SHAFT PULLER.

Application filed November 27, 1926. Serial No. 151,139.

This invention relates to drive shaft pullers and more particularly to a device for disengaging the drive shaft of a well known make of automobile from the coupling, by means of which this shaft is connected with the worm forming a portion of the differential assembly with which the drive shaft is associated.

An important object of the invention is to provide a device of this character which may be very readily applied to the drive shaft and coupling and which will greatly facilitate removal of the shaft from the coupling.

A further object of the invention is to provide a device of this character which may be very readily and cheaply manufactured and which will be durable and efficient in service.

These and other objects I attain by the construction shown in the accompanying drawings, wherein for the purpose of illustration is shown a preferred embodiment of my invention and wherein:—

Figure 1 is a sectional view showing a puller constructed in accordance with my invention applied to the shaft to remove the coupling therefrom;

Figure 2 is a side elevation thereof as applied to the shaft;

Figure 3 is a section on the line 3—3 of Figure 1.

Referring now more particularly to the drawings, the numeral 10 generally indicates the drive shaft of an automobile and 11 a coupling by means of which the drive shaft is connected with the worm 12, which forms a portion of the differential assembly with which the shaft is associated.

In accordance with my invention, I provide a puller comprising male and female elements 13 and 14 adapted to engage the coupling and shaft respectively. The female element has a bore 15 receiving the shaft and has directed through its body set-screws 16 extending radially to the bore and adapted to engage the shaft 10 and hold the female element against movement thereon. The bore 15 communicates with an enlarged bore 17, the wall of which is provided with screw threads for engagement with threads

formed upon the exterior of the male member 13. The male member 13 has a bore 18 slidably receiving the shaft and is formed at one end with a polygonal head 19 with which a wrench may be engaged.

In the use of the device, the drive shaft having been removed from its housing (not shown), the male member is threaded into the female member as far as it will go and the assembled unit slid upon the shaft 10 with the male member in advance until this male member comes in contact with the coupling. The set-screws 16 are then tightened to hold the female member firmly against any movement with relation to the shaft after which a wrench may be applied to the male member 13 to jack the coupling from the shaft.

It will be obvious that by use of a device of this character, the coupling may be very readily removed without marring the shaft at a point where the shaft has bearing in its mounting.

It will also be obvious that the construction hereinbefore set forth is capable of a certain range of change and modification without materially departing from the spirit of the invention and I accordingly do not limit myself to such specific structure except as hereinafter claimed.

I claim:—

In a device for removing couplings from shafts, a female member having at one end a bore adapted to receive and slidably fit the shaft, means projecting through the wall of the member at said end for holding the member against displacement longitudinally of the shaft, the opposite end of the member having an enlarged bore the wall of which is threaded, an exteriorly threaded male member engaged in said bore and having a bore slidably receiving the shaft, the projecting end of said male member being adapted for engagement with a wrench whereby it may be rotated and having its end face adapted for engagement with the coupling to be removed.

In testimony whereof I hereunto affix my signature.

WILLIAM J. RAPPLEY.
